UNITED STATES PATENT OFFICE.

HARRY D. HAMILTON, OF WINTHROP, AND CHARLES B. TIBBETTS, OF WALPOLE, MASSACHUSETTS, ASSIGNORS TO UNITED SHOE MACHINERY CORPORATION, OF PATERSON, NEW JERSEY, A CORPORATION OF NEW JERSEY.

DISPENSING APPARATUS.

Application filed October 29, 1920. Serial No. 420,442.

To all whom it may concern:

Be it known that we, HARRY D. HAMILTON and CHARLES B. TIBBETTS, citizens of the United States, residing in Winthrop, in the 5 county of Suffolk and Commonwealth of Massachusetts, and Walpole, in the county of Norfolk and Commonwealth of Massachusetts, respectively, have invented certain Improvements in Dispensing Apparatus, of which the following description, in connection with the accompanying drawings, is a specification, like reference characters on the drawings indicating like parts in the several figures.

15 This invention relates to dispensing apparatus, such as containers for fluids, of which the cement employed in shoe making and repairing furnishes an example. The general practice followed by shoe shop 20 workers and shoe repair men in dispensing cement for their operations involves, as far as we are aware, the use of containers which have movable elements liable to become stuck by the accumulation of dried cement, which 25 expose the contents not in use to rapid evaporation and consequent deterioration, which allow the brush or other applying device to become hardened and deformed, and which are difficult of access in obtaining 30 the contents or to keep clean. Objects of our invention are to overcome all these difficulties by the provision of a simple and inexpensive dispensing apparatus, which insures the free supply of the entire body of 35 fluid being dispensed, with but slight exposure to evaporation, and which permits the applying brush to be maintained flexible and in its natural form, and the fluid container to be easily cleaned.

40 In the attainment of these objects, we furnish, as a feature of the invention, a novel container and a cover therefor, the latter having a tubular portion within the container. This tubular portion preferably 45 extends into proximity with the bottom of the container, entering the fluid therein to give a relatively small exposed area into which the applying device may be dipped, the remainder of the surface being shielded 50 against evaporation by means of a preferably hermetical closure at the juncture of the container and cover. The tubular delivery portion is shown as passing outside the cover, it there being engaged by a clo-

sure which serves to support the applying device. This closure protects the surface of the fluid within the tubular portion, into which the applying device dips, against evaporation when said applying device is not in use, and by having frictional engagement between the closure and applying device, the latter may be adjusted vertically to establish and maintain correct relation between it, the surface of the fluid and the end of the tubular portion.

65 One of the many embodiments of the invention is hereinafter more particularly described and claimed, reference being had to the accompanying drawing, in which—

Fig. 1 illustrates in broken perspective 70 one form of our improved container;

Fig. 2 is a side elevation, with the container in section, showing the step of assembling the dispensing cover with the container to establish the barometric feed;

Fig. 3 is a broken perspective of the container, having assembled with it the delivery and applying devices; and

Fig. 4 shows in broken side elevation the delivery device employed for protecting the 80 applying device.

The numeral 10 designates a pail, or other suitable container, which may be constructed of sheet metal. The container is preferably of considerable diameter as compared 85 with its height. The top of the container has an opening 14 of a diameter approaching that of said container, it being here shown as arranged for engagement at its inner edge by the well-known friction type 90 of cover, illustrated at 16 in Fig. 1 of the drawing. This cover, when forced into place with direct rectilinear movement, seals the container against evaporation of the contents while it is being stored or transferred, 95 and yet may be removed readily to give access to the contained cement or other fluid. Adapted to be substituted for the storage cover 16 is a dispensing cover 18, which may also serve, when separated from the 100 container, as a brush support and protector. The dispensing cover is arranged to furnish an air-tight joint between the inner edge of the container top and the cooperating edge of the cover, this being, in the present instance, by its frictional engagement. Opening through the center of the cover 18 is 105 a delivery tube having a portion 20 depend-

ing from the cover, and reaching a plane in proximity to the bottom of the container 10. The diameter of the portion 20 is substantially less than that of the container, 5 it leaving an annular space of considerable width between the tube and container walls. Rising above the cover 18 is an upwardly and inwardly inclined portion 22 of the tube, this being continued by an outwardly inclined tubular portion 24. These adjacent tube portions thus form oppositely inclined frusto-conical sections. Arranged for contact with the upper edge of the portion 24 is a closure 26, in the form of a circular 15 disk of preferably flexible material, as rubber. At the center of this closure is an opening 28 to engage, with some frictional resistance against movement through it, the handle 30 of such an applying device as a 20 brush 32.

The containers may be of such a capacity that they will hold some quantity of cement convenient for use by an operative, say, one or two quarts. When prepared for sale, they 25 may be closed either by a storage cover 16 or the dispensing cover 18. The former arrangement is better suited for factory use, since one of the dispensing covers may be utilized with a plurality of the containers 30 held sealed by the cover 16 in storage. For shoe repair men it may be convenient to market the container with the dispensing cover, thereafter containers with the storage cover being purchased and the dispensing 35 cover obtained with the first container used therewith. When the container is put out closed by the cover 18, the portion 24 of the dispensing tube may be covered by a soft metal seal, or may have inserted in it a 40 stopper, the inclination being such as to facilitate this. Assuming that the apparatus is being employed in a shoe factory, an operative, upon beginning work, will receive from the stock room a container closed by 45 its storage cover, and will then remove this and substitute the dispensing cover. The upper end of the delivery tube, while the lower portion 20 is being inserted in the contents of the container, may be sealed by 50 the palm of the hand, as illustrated, in Fig. 2 of the drawings, or may be closed by the disk 24 carrying the brush. In the latter case, the efficacy of the closure is increased by having a ring of cement upon the upper 55 edge of the tube portion 24. With the outer end of the delivery tube closed in either manner, it and the contained body of air displace a portion of the cement upwardly between the portion 20 and the cylindrical 60 wall of the container, and before breaking the closure at the top of the tube, the outer edge of the cover 18 is pressed into engagement with the top 12 of the container to form a seal along this line. The latter 65 closure being air-tight, there will be held

by atmospheric pressure an elevated body of cement in the annular space about the delivery tube, but a small quantity rising into the lower end of the tube. The handle of the brush 32 may then be adjusted through 70 the closure 26 until the bristles dip to the desired extent in the cement within the tube, when the closure rests upon the tube portion 24. The apparatus is now ready for use. When the operator withdraws the brush to 75 apply the cement held by its fibers to the work, the inward inclination of the tube portion 22 tends by its contact to straighten the fibers and to remove the excess of cement therefrom. Cement received upon this portion 22 flows down it to the tube portion 20, and is returned to the body within the container, being prevented from dripping upon any portion of the brush, as might be the 80 case were this contracted section of the tube 85 parallel to the cylindrical portion, instead of inclined. When the charge upon the brush has been applied and it is to be returned to the container for a fresh supply, the downward and inward inclination of the 90 portion 24 of the tube facilitates its introduction without disturbing the normal parallel relation of the fibers, and drops of cement falling upon this wall 24 are conducted over the lower tube sections to the 95 supply in the container without coming into contact with the brush. After the entire elevated portion of the contents of the container has been used and the level of the cement inside and outside the tubular portion 100 20 is the same, the brush handle may be lowered through its supporting disk to permit the operator to use the entire contents. It is to be observed that prior to this lowering of the fluid level, the entire body of 105 cement between the tube and container walls is protected against evaporation, there only being exposed to the air a surface of limited area within the tube.

At the close of his work, the operative 110 removes the dispensing cover 18 and sets it upon the bench, or other suitable surface, the lower edge of the portion 20 coming in contact with this support. The brush at this time should be so positioned in the 115 closure 26 that the lower extremities of its fibers are above the bottom edge of the tube. When thus disposed, the applying portion of the brush, it will be seen, is entirely enclosed, laterally by the delivery tube, at 120 the top by the closure 26 and the brush handle, and at the bottom by the supporting surface. This, while not entirely air-tight, gives little opportunity for evaporation, and the drip from the tube tends to increase the 125 perfection of the enclosure. Moreover, if, when the brush is thus arranged, it carries in its fibers some of the cement, this, dripping upon the supporting surface, will flow to the edges of the tube, aiding in effecting 130

a seal. There is also usually a certain amount of cement upon the under side of the closure 26 which will more effectively seal the line of contact between this and the 5 upper extremity of the delivery tube. The container is sealed by the replacement of the storage cover 16 and is returned to the stock room, or it may be cleaned out and re-filled with fresh cement and then sealed. In 10 doing this, it will be obvious that, since the diameter of the opening in the top of the container is nearly as great as that of the container itself, any cement which has accumulated upon the sides or bottom of the 15 container may be readily removed by the insertion of the hand. When the operative resumes work, he may be provided with the refilled container, or a fresh one, and utilizes the contents in the same manner as already 20 described.

Having described our invention, what we claim as new and desire to secure by Letters Patent of the United States is:

1. A dispensing apparatus comprising a 25 container, and a cover therefor having a tubular portion with its wall inclined upwardly and inwardly outside the container.

2. A dispensing apparatus comprising a 30 container, and a cover therefor having a tubular portion including oppositely inclined frusto-conical sections extending outside the cover.

3. A dispensing apparatus comprising a 35 container, a cover therefor having a tubular portion extending upon its opposite sides, a

closure separably engaging the tubular portion outside the container, and an applying device supported upon the closure.

4. A dispensing apparatus comprising a 40 container, a cover therefor having an opening, a closure for the opening, said closure being of yieldable material and arranged to co-operate with the cover outside the opening, and an applying device supported upon the closure.

5. A dispensing apparatus comprising a 45 container, a cover therefor having an opening, a rubber disk furnishing a closure for the outside of the opening, said closure being provided with an opening, and a brush 50 having its handle in frictional engagement with the wall of the closure opening.

6. A dispensing apparatus comprising a 55 container, a cover therefor having a tubular portion with its wall inclined upwardly and inwardly outside the container, and a brush supported upon the tubular portion.

7. A dispensing apparatus comprising a 60 container, a cover forming with the container an air-tight joint and having a tubular portion extending into said container, a closure for the tubular portion, and a brush supported upon the closure and having its applying portion wholly within the tubular portion of the container.

In testimony whereof we have signed our names to this specification.

HARRY D. HAMILTON.
CHARLES B. TIBBETTS.
